AUTOMATIC ACTUATING MECHANISM

Karl Schwartz, Dusseldorf, Germany

Application October 4, 1938, Serial No. 233,303
In Germany April 2, 1937

1 Claim. (Cl. 161—1)

This invention relates to an automatic actuating mechanism or time switch which is particularly intended for use in making photographic films taken kinematically at intervals, but which 5 can, however, be also used with advantage for releasing or operating other working processes at definitely adjustable intervals of time, with provision, if necessary, for automatic repetition of the release or operation effected by the mechanism, at regular and adjustable intervals of time.

According to the invention, it is proposed to add up individual units of time usually not adjustable, by means of a mechanical predetermining mechanism of known character of decimal 15 or similar construction, in which in consequence of its construction the desired actuating movement is released after attaining a sum adjustable therein.

If these releases are to be repeated periodically, 20 then according to the invention a predetermining mechanism also of known character is to be used which directly following a release automatically effects a resetting of the predetermining mechanism to the originally adjusted value, so that the 25 addition is again commenced and the process is subsequently continuously repeated.

According to the invention therefore there is provided a time switch comprising a timing mechanism, a predetermining mechanism which 30 can be adjustably set to indicate a required time period, a driving connection between the timing mechanism and the predetermining mechanism whereby the latter is operated step by step in accordance with given time units, and means where- 35 by a switching operation is effected by the predetermining mechanism when the same reaches the time period set thereon.

To produce the time units, a driving system of 40 known character regulated as to time can be used, for example a clockwork or a synchronous motor, the spindle of which makes one revolution in a certain period or closes a contact with each revolution, which say by means of a lifting magnet 45 effects the running on of the predetermining mechanism. This method of driving does not therefore directly control the periods of time, as with the previous installations, but only produces the time units which are then added up by the predetermining mechanism.

In order that the invention may be readily understood one embodiment shown by way of example in the accompanying drawing will now be referred to. In the drawing:

55 Figure 1 is a diagrammatic representation of

a timed actuator according to the invention seen from the rear, and

Figure 2 is a diagrammatic view in side elevation from the left of Figure 1.

The principal parts of the timed actuator shown 5 are the time-regulated driving agent or timing mechanism 1 (e. g., synchronous motor), the predetermining mechanism 2 and the resetting magnet 3. With each revolution of the driving system 1 the predetermining mechanism 2 is moved 10 forward one step to register one unit, the means employed for effecting this step by step actuation of the meter 2 consisting of a locking tooth or ratchet 4 which is reciprocated by an eccentric on the timing mechanism spindle and which co- 15 operates with a ratchet wheel 5, which is secured to rotate with a toothed wheel 6 meshing with a driving spur-wheel 7 for the first numeral roller or totaliser wheel 11. In a manner well known, 20 this totaliser wheel at each tenth step turns the roller or totaliser wheel 12 of the next higher denomination which in its turn actuates the next higher wheel 13 and so on for all the wheels 13-15. The consequence of this decimal construction is that with the five numeral rollers 25 or totalisers shown,—referred to herein as system I,—any number between 0 and 99999 can be metered.

Coupled with each of the individual numeral rollers of this system (System I) is a roller or totaliser wheel (21-25) of a second system (system II). These rollers 21-25 are freely rotatable on the spindle 8 and are only moved forward by the movement of the roller corresponding thereto of the system I.

Rigid with each of the five rollers 21-25 of the 30 system II, is a cylindrical disc (31-35) which at a point of its circumference has a cam in the form of a notch-like depression 41-45. On these 40 five discs there rests under the pressure of the spring 10, a five-fingered feeler lever 9 and it will be observed that only when all the five notches, 41-45, are in line, can the lever 9 rock clockwise (see Figure 2) and thereby close both 45 the switch contacts c for effecting the desired actuating or releasing movement, and the contacts c¹ into the operating circuit for the resetting magnet 3, the function of which will be hereinafter described.

This important rocking movement of the feeler lever 9 when the notches 41-45 are aligned is arranged to take place when all the rollers of the system II indicate the value "0" in the front aperture 16 of the housing. As long as any roller 55

of the system II is not in the zero position, the corresponding finger of the lever 9 is supported by the circular portion of the periphery of the appropriate disc (31-35) and the rocking movement of the lever 9 cannot occur.

As the two numeral roller systems I and II are oppositely coupled, whilst the numbers however are arranged in similar order the system II subtracts whilst the system I adds up.

- 10 If now before commencing the actual metering process, the rollers of the system I are placed in the zero position and those of the system II—which can be disengaged from system I by the switching out lever 17—are positioned to indicate the numerical sum on reaching which the switching operation at contacts c and c¹ is to be effected then on the coupling of the systems with the time-regulated driving mechanism 2, the system I will commence to add commencing from "0," 20 whilst the system II commences to subtract from the number initially set thereon.

At the moment when the system I reaches the desired number the five rollers of the system II will have reached the value "0." The five-fingered lever can then rock clockwise (see Fig. 2) and the switching operation is effected.

- If the time-operated mechanism is to repeat this process periodically, then according to the invention a resetting device is provided by which, 30 directly following the switching operation there follows the resetting of the predetermined mechanism to the originally adjusted or set number so that a fresh addition and respectively subtraction is commenced. In order that no falsification of 35 the duration of time of operation takes place, this resetting must naturally be so rapidly terminated that the metering mechanism is ready for a fresh predetermined—that is, the system I is again on "0," and the system II on the desired number—before the eccentrically moved ratchet tooth 4 engages the next tooth of the ratchet wheel 5. As the release or switching operation takes place approximately towards the end of a forward movement of the ratchet tooth the period 40 of the return movement of the ratchet tooth is available for the resetting. If there is fixed as the basic time unit of the driving spindle, one revolution per second, then the resetting time of half a second must not be exceeded.

- 50 In the embodiment illustrated, the resetting is effected by the magnet 3.

Rigid with each of the numeral rollers of the system I, there is a heart-shaped cam piece (51-55) adjacent to which is disposed one arm of a five-armed lever 19. These arms carry on the end adjacent the cam pieces, corresponding counter cams which are so shaped that when pressed against the heart pieces they cause the latter to be rotated into a particular position irrespective of their position at the time the arms of the lever 19 engage therewith. This position corresponds to that of "0" of the upper numeral roller system I which, on its part, can be read off in the aperture 18.

- 65 During this resetting, the numeral rollers 11-15 are mutually disengaged, the decimal actuating or transfer wheels 61-64 and the driving spur-wheel 1, being carried on a spindle 20 which is rocked anti-clockwise (see Fig. 2) with the resetting lever 19, against the pressure of the spring 26, to disengage the wheels 1, and 61-64 from the totaliser wheels 11-15 and the wheel 6.

70 Anticlockwise movement of the resetting lever 19 is caused by the resetting magnet 3, the circuit of which, as already mentioned, is closed over

contacts c¹, when lever 9 rocks clockwise upon the notches 41-45 coming into line. In this way it is ensured that the resetting takes place actually directly following the release or switching operation. As the rollers of the system II remain 5 coupled with those of the system I during the resetting, these also are again brought back into the originally adjusted position, whereupon the feeler lever 9 is disengaged from the notches 41-45 and rocked anticlockwise to open the contacts 10 c and c¹. The resetting magnet 3 de-energises so that the resetting lever 19 again returns to the initial position shown with the result that the numeral rollers are again coupled and thus the original initial condition is re-established. If— 15 as above indicated—all the processes connected with the release and the resetting have taken place within half a revolution of the spindle of the driving mechanism, the predetermined mechanism commences again with a fresh metering of the time units, when after reaching the desired number, the release and resetting again takes place, and so on. The process is repeated as often as desired in positive and always constant intervals of time, which are registered by 20 25 the predetermined mechanism.

In order to eliminate the resetting magnet and thereby simplify the construction of the apparatus, it is proposed to use a predetermined mechanism, also of known construction, in 30 which for example two complete numeral roller or totaliser wheel systems are so coupled together that the one adds up whilst the other subtracts. Before setting in operation, the one system is adjusted to zero and the other to the desired sum or number. During the metering therefore, the one runs up to the desired number, whilst the other runs down to zero. When this instant is reached, the operating movement is released i. e., the switching operation takes place, 40 when at the same time a change gear is mechanically so changed over that the direction of drive of the two systems is reversed. On a further actuation, therefore, the first system commences to subtract, whilst the second one 45 adds up. This oscillating process is also continuously repeated.

It is furthermore easily possible to supply the numeral rollers of the metering system not as usual in decimal arrangement but with a 50 graduation which corresponds to the standard system of measuring time. Thus, for example, for a sub-division into seconds, minutes and hours, there will be a decimal roller and six-division roller for the seconds, a decimal roller 55 and six-division roller for the minutes, and a twenty four-division roller for the hours. This arrangement obviates the troublesome conversion of hours and minutes into seconds and consequently gives important advantages in the ad- 60 justment.

The particular advantage of the improved timed actuator lies above all in the practically unlimited range within which the actuating times can be simply and rapidly adjusted. In this the 65 possible errors in actuating times must necessarily always be only a fraction of the smallest adjustable operating time. Whereas, hitherto—at least in the scope of simple technical means—it was only possible to arrange switching times 70 with a time ratio of about 1:60 or at the most 1:3600 with sufficiently small errors in actuating times, the improved apparatus easily permits, according to the number of stages of the numeral roller system, the bridging over of a 75

time ratio of 1:100,000, 1:1,000,000 or more, all the intermediate values being attainable with a graduation of one unit. The error in switching time here remains, as already mentioned, 5 always smaller than 1.

If, to give an example, a minute is chosen as the unit of operating time, that is, if the axis of the predetermining mechanism is driven at exactly one revolution per minute, then with a 10 five place numeral roller system the time periods possible may vary between 1 and 100,000 minutes (that is, about 2½ months). If, for example, the release of the intended actuation is desired at exactly 24 hours after switching in 15 the timed actuator, then the numeral roller system will be adjusted to $60 \times 24 = 1440$ minutes and the release will take place—presuming correct running of the driving mechanism to time—positively to the fraction of a minute exactly 20 after 24 hours.

In its principal respect the improved apparatus has been developed for the production of series photographs taken at intervals. But the operating mechanism can also be used with advantage where the so-called slow acting relays 25 or time switches of present construction have either worked too inaccurately or in which the adjustability to any desired intervals of time was too complicated, e. g., for the actuation of 30 registering apparatus, drop loop instruments, remote ignitions, control of operating relays, long duration experiments in laboratories, and other experimental fields, retarded switching-in and out of any current circuits, and the like.

In the claim, the mechanism according to this 35 invention will be referred to as a timed actuator, and it will be understood that the release or operation effected after a predetermined set time in-

terval may be the closing or opening of electrical circuit contacts, or the movement of any member which is to be controlled periodically.

I claim:

In a timed actuator including a timing mechanism for driving the actuator, a predetermining mechanism consisting of two sets of coupled totaliser wheels, driving and transfer pinions for the primary set of wheels and means for uncoupling the two sets for adjustably setting the 10 secondary set of wheels to indicate a required time period and the primary set to zero, a driving connection between the timing mechanism and the primary set of wheels whereby the latter are actuated step by step towards the time 15 period initially indicated on the second set of wheels while the latter are zeroised, a plurality of cam discs each associated with a totaliser wheel of the secondary set, a switching member 20 cooperating with said cam discs to move when the cams are aligned in the zeroised position of the secondary wheels, and thereby effect a switching operation, resetting means comprising a rocking reset lever on which the driving and transfer pinions of the primary set of wheels 25 are carried, a resetting relay controlling the reset lever and having contacts which are disposed to be closed by the switching movement of the switching member whereby the relay is energised to lock the reset lever and disengage the said driving and transfer pinions from the primary set of wheels, a plurality of reset cams one secured to rotate with each primary wheel, and arms on the reset lever which engage said reset cams upon rocking of the reset lever to return 30 the primary wheels and the secondary wheels coupled therewith to the initial set positions.

KARL SCHWARTZ.
